(57) **CLAIM**

The ornamental design for a control enclosure, as shown and described.

DESCRIPTION

FIG. 1 is a top and front perspective view of a control enclosure showing our design in the open position;

FIG. 2 is a top plan view thereof;

FIG. 3 is a bottom plan view thereof;

FIG. 4 is a front view thereof;

FIG. 5 is a rear view thereof;

FIG. 6 is a right side view thereof;

FIG. 7 is a left side view thereof; and,

FIG. 8 is a top and front perspective view of the control enclosure of FIGS. 8-15 in the closed position.

The broken lines show environmental matter that forms no part of the claimed design.
